(57) **CLAIM**

The ornamental design for a top for a room divider panel, as shown and described.

DESCRIPTION

FIG. 1 is a front elevation view of a first embodiment of a top for a room divider panel according to the present invention; the rear elevation view is a mirror image hereof.

FIG. 2 is an isometric view of a first embodiment of the top for a room divider panel shown in FIG. 1.

FIG. 3 is a right side view of the top for a room divider panel shown in FIG. 1.

FIG. 4 is a left side view of the top for a room divider panel shown in FIG. 1.

FIG. 5 is a top view of the top for a room divider panel shown in FIG. 1.

FIG. 6 is a bottom view of the top for a room divider panel shown in FIG. 1.

FIG. 7 is an isometric view of a second embodiment of the top for a room divider panel shown in FIG. 1.

FIG. 8 is a right side view of the top for a room divider panel shown in FIG. 7.

FIG. 9 is a left side view of the top for a room divider panel shown in FIG. 7.

FIG. 10 is a top view of the top for a room divider panel shown in FIG. 7; and,

FIG. 11 is a bottom view of the top for a room divider panel shown in FIG. 7.

The bottom for the room divider panel is shown in broken lines and forms no part of the claimed invention.
